FAUCET

John N. Anagno, Lynn, Mass.

Application June 3, 1939, Serial No. 277,146

4 Claims. (Cl. 225—6)

This invention relates to beverage dispensing apparatus and particularly to improvements in draw-off or delivery faucets for incorporation in apparatus for use in storing and dispensing beer and other carbonated liquids.

The object of the invention is primarily to provide an improved delivery faucet of the type shown and described in my co-pending application for patent, Serial Number 190,527, filed February 16, 1938.

To these ends I have provided certain improvements in faucets of the class referred to as set forth in the following description, the several novel features of the invention being separately pointed out and defined in the claims at the close thereof.

In the accompanying drawings—

Figure 1 is a central vertical longitudinal sectional view of my improved faucet showing the same mounted in a wall of a refrigerator or the like.

Figure 2 is a side view, partly in section, of the valve member hereinafter described.

Figure 3 is a section on line 3—3 of Fig. 2.

Figure 4 is a section on line 4—4 of Fig. 1.

Figure 5 is a side view, partly in section, of the spout element or section of the body hereinafter described.

Figure 6 is a side view, partly in section, of the tubular shank element or section of the body.

Figure 7 is a sectional view of the coupling member hereinafter described.

The illustrated embodiment of my invention is a delivery faucet comprising a body consisting of a straight tubular shank section 10 and a downwardly curved tubular nozzle section 11 rigidly fastened together by an annular coupling member 12.

The shank section 10 of the body extends through a hole formed through the rear wall 13, Fig. 1, of a refrigerator or other fixture and is exteriorly threaded to receive upon it a nut 14 by means of which the body is fixedly clamped to said wall, and also a coupling member 15 which serves to fixedly clamp the flanged end of a delivery tube 16 against a rubber or leather gasket 17 disposed between said flanged end and the adjacent inner end of shank section 10.

The wall 13 is the back wall of a refrigerator compartment 18 which may be provided within a bar or counter of which said wall forms part. It is customary to provide a cooling unit (not shown) within compartment 18, said unit being controlled and operated to maintain therein a desired predetermined temperature. The com-

partment 18 is provided for the reception of a barrel containing beer or other carbonated liquid, said barrel being provided with an outlet that is connected with the inlet 19 of the faucet by eight or nine feet of metal tubing 16 having an inside diameter of five thirty-seconds ($\frac{5}{32}$) of an inch, or thereabouts. A strainer 20 may, as shown, be provided within the inlet 19.

The inner end of the nozzle section 11 is counter-bored to provide a socket 21, Figs. 5, 6 and 7, into which is telescopically fitted the outer end portion 22 of the shank section 10, while the exterior of said inner end portion is provided with screw threads 23 for engagement with threads 24 provided upon the interior of coupling member 12. Said coupling member 12 is also provided upon its interior with an annular shoulder 25 which bears against an annular shoulder 26 on shank section 10 to clamp the end of the latter within socket 21.

The tubular shank section 10 is made internally with a relatively large cylindrical valve chamber 27 whose outer end is connected by a relatively small port 28 with the inner end of a tubular metal lining member 29 that is forcibly fitted within the nozzle section 11, said lining member providing a conduit through which deliveries are made from the faucet. Only the opposite end portions of the lining member 29 are in contact with the metal of the nozzle section 11 while the intermediate portion of said lining member extends through a chamber 30 provided upon the interior of the nozzle section. This chamber is larger than the outside diameter of lining member 29 so that the latter is surrounded throughout the greater portion of its length by an insulating dead air space 31.

The outlet port 28 is the central aperture of a rubber gasket or annulus 32 which occupies a shallow counterbore 33, Fig. 6, provided at the outer end of shank section 10, said annulus being tightly clamped between the two sections of the body and serving not only to close the adjacent joints between said parts, but also as a yielding seat for an elongate valve member 34.

Valve member 34 is slidably mounted within chamber 27 and normally is yieldingly urged endwise toward and against seat 32 by the pressure of the beer or the like supplemented by a coiled spring 35 disposed within the inlet end of chamber 27 between the valve member 34 and a shoulder 36 provided upon the interior of body section 10.

The elongate valve 34 is made at its outer end with a boss extension 37 to co-operate with a

radial arm 33 depending from a transversely disposed rocker spindle 39 which extends through, and is journaled in, a bearing provided in nozzle section 11 above lining member 29, the latter 5 and nozzle section 11 being formed, respectively, with longitudinal slots 40 and 41 to accommodate said arm and permit of swinging movement of the latter.

At its one end the rocker spindle 39 is provided with an upstanding handle 42 whose hub is provided with a laterally projecting stud 43 occupying a socket or groove 44 provided upon the outside of nozzle section 11 and whose outer end wall serves as a stop to limit the movement 15 of arm 42 toward the refrigerator.

When the handle 42 is swung in the opposite direction to effect delivery of the beer or the like, the spindle 39 is rocked in a direction to cause the arm 38 to engage the boss 37 and open 20 valve 34, movement of the valve in this direction being limited by the engagement of its inner end with the longitudinally disposed end portion 45 of spring 35.

When the handle 42 is swung toward the left, 25 Fig. 1, the pressure of the beer, supplemented by the pressure of spring 35, acts to quickly thrust the valve endwise into position against its seat 32.

As shown in Fig. 4 the nozzle section 11 is 30 made with two aligned ports 46 and 47, one below and the other above the spindle 39, the said port 46 communicating with the interior of lining member 29 and the port 47 communicating with the outside atmosphere. These two ports 35 cooperate with a port 48 formed diametrically through the spindle 39 to vent the upper end portion of the interior of said lining member when the valve is closed and the handle 42 occupies its full line position shown in Fig. 1. When 40 the handle 42 is swung downwardly into the position indicated by dotted lines in Fig. 1, the opposite ends of the port 48 are out of register with the ports 46 and 47 so that the upper end portion of the interior of lining member 29 is not 45 vented while making a delivery.

The arm 38 is made with a cylindrical shank occupying a socket or hole 49 formed transversely through spindle 39 and said shank is fixedly clamped within said socket by means of a screw 50.

The end of spindle 39 opposite the handle 42 is formed with a threaded countersink 51 into which is screwed the threaded shank of a capstan screw 52 between whose head and nozzle 55 section 11 is compressed a spring washer 53 which may be made after the fashion of a lock washer. The head of screw 50 is disposed within the countersink 51 and its threaded shank occupies a tapped hole at the bottom of the countersink 51.

The vent conduit 46-48-47 which is closed 60 while making a delivery and automatically opened when the parts are permitted to return to their normal positions, provides a quick draining feature which avoids dripping after delivery 65 and tends to maintain that portion of the interior of the faucet that is outside of valve member 34 sanitarily dry while not in use.

The elongate valve member 34 is, as shown in 70 Figs. 2 and 3, made from a length of metal tubing having its opposite ends closed by plugs which are fitted within the ends of the tubing so as to provide leak-tight joints. Thus the valve member 34 is circular or cylindrical throughout the greater portion of its length. The 75 plug 54 at the outer end of the valve member is

made parti-spherical so as to impart a streamline form, which avoids agitation and which properly engages its seat 32. The boss 37 is formed upon the plug 54.

The valve member 34 is slidably supported centrally within the cylindrical chamber 27 by means of a plurality of bosses 55 projecting from the intermediate cylindrical tubular portion of the valve member. The body of the valve member is made predeterminedly less in diameter than 10 the chamber 27 and is maintained concentric with the latter by the bosses 55. In practice I make the chamber 27 .725 of an inch in diameter while the outside diameter of the valve member 34 is made .705, .700 or .695 of an inch in diameter according to the pressure under which the beer or the like is delivered into the chamber 27 through the inlet port 19. This provides a flow-retarding constriction within the faucet and surrounding the valve member 34 which, together 20 with the streamline form of the outer end of the valve member, avoids excessive foam. Furthermore, it will be observed that the valve member serves as a pressure-reducing valve because of the elongate constricted passageway provided between said member and the surrounding wall of chamber 27. Also the valve centralizing bosses 55 insure proper cooperation between the valve member and its seat at all times and prevent any lateral displacement or fluttering of the valve. 30

Apparatus, such as the above described, are at times cleaned out and this is usually accomplished by connecting the delivery end of nozzle section 11 with a supply of cleansing liquid under pressure or head so that said cleansing liquid is 35 forced reversely through the faucet and the tube 16 connected therewith. Therefore, in order to prevent the valve member 34 from seating against the rear or inner wall of chamber 27 one end of the spring 35 is bent so as to extend longitudinally toward the valve member as at 45 which provides a stop which prevents the valve member from closing chamber 27 at its inner end when the cleansing fluid is forced into the faucet as described. 45

What I claim is:

1. A faucet of the character described comprising a body made with a delivery conduit including an elongate valve chamber of relatively large cross-sectional area and into one end of 50 which beer or the like is supplied under pressure; an outlet port at the opposite end of said chamber; a valve seat within said chamber surrounding said outlet port; an elongate valve member disposed wholly within said delivery conduit and made upon its exterior with bosses by which it is 55 slidably supported independently and centrally within said chamber by the portion of said body surrounding said chamber so that it is movable longitudinally toward and from said seat and normally urged independently endwise against the latter by the pressure of the beer or the like to close said outlet port, the cross-sectional area of said valve member being predeterminedly less than the cross-sectional area of said chamber thereby to provide an elongate constricted pressure-reducing passageway through which the beer or the like is forced from the inlet end of 60 said chamber to said outlet port when said valve member is shifted longitudinally away from said 65 seat, and a rocker spindle independently supported by said body and provided with a radial arm projecting into said conduit so that it is operable to adjust said valve member axially away from said seat by abutting engagement with 70 75

5

10

15

20

one end of said valve member thereby to open said outlet port when said spindle is rocked in one direction, said rocker spindle being provided with a handle disposed outside of said body by means of which it is operated.

2. A faucet of the character described constructed in accordance with claim 1 and wherein said elongate valve member comprises a body portion consisting of a length of thin metal tubing and two plugs closing the opposite ends of said metal tubing so as to exclude liquid from the interior of the latter, and wherein said length of metal tubing is molded to provide said bosses upon its exterior by which the valve member is slidably supported centrally within said valve chamber.

3. A faucet of the character described constructed in accordance with claim 1 and wherein said body comprises a tubular shank section, a tubular nozzle section whereof one end is telescopically engaged with one end of said shank

section, and a coupling member rigidly fastening said sections together, and wherein a gasket of resilient material is confined in position between said two sections so as to provide said outlet port and said seat.

4. A faucet of the character described constructed in accordance with claim 1 and wherein said body comprises a tubular shank section, a tubular nozzle section whereof one end is telescopically engaged with one end of said shank section, and a coupling member rigidly fastening said sections together, and wherein a gasket annulus of resilient material is confined in position between said two sections so as to provide said outlet port and seat, said gasket annulus being tightly clamped between the two sections of the body and serving not only to close the adjacent joints between said parts but also as a yielding seat for the elongate valve member.

JOHN N. ANAGNO.
